(57) **CLAIM**

The ornamental design for a combined Skinner and survival knife, as shown and described.

DESCRIPTION

FIG. 1 is a perspective view of a combined Skinner and survival knife showing my new design;

FIG. 2 is a front view, the rear view being a mirror image thereof;

FIG. 3 is a top view thereof;

FIG. 4 is a bottom view thereof;

FIG. 5 is a side view thereof; and,

FIG. 6 is an opposite side view thereof.

In FIG. 1, the broken lines showing the environmental structure for purposes of illustrating the combined Skinner and survival knife in a condition of use. The broken lines and the structure they depict form no part of the claimed design.
